LESS WIRE & FENCE COMPANY, OF ADRIAN, MICHIGAN, A CORPORATION OF DELA-
WARE.

METHOD AND APPARATUS FOR MANUFACTURING HARD-STEEL FENCEPOSTS.

Application filed December 29, 1922. Serial No. 609,682.

To all whom it may concern:

Be it known that we, VERNON HOXIE and MARTIN C. EPKE, citizens of the United States, and residents of Adrian, in the county of Lenawee and State of Michigan, have made an invention appertaining to a Method and Apparatus for Manufacturing Hard-Steel Fenceposts; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to fence posts of the hard steel type, and particularly to a method and apparatus for providing the same with integral tongues for holding fence wires to the post.

In the manufacture of metallic fence posts practically all manufacturers, so far as we are aware, employ a metal made from old rails and which is a quality of steel called "rail carbon", and is usually known in the steel mills as "Sunday night steel", being a steel upon which mistakes have been made. This steel is usually too high in carbon for ordinary commercial purposes and is used mainly for concrete reinforcing bars, some parts of agricultural machinery and metallic fence posts, all of which articles require high tensile strength. This metal is very hard to work and has been found impractical for use where punching and forming operations are required.

In the use of metallic fence posts it is necessary to provide means for securing wire fabric thereto. On account of the hardness of the steel from which these parts are made it has been found impractical to form integral tongues on a post for engaging with the wires, as has been done in some soft steel posts, and the posts have therefore commonly been provided with oblong holes and special staples are furnished with the posts for insertion into the holes to fasten the fabric to the post. This manner of fastening the fabric has been very annoying to manufacturers, as well as to users, as the ordinary fence staple will not fit, and the special staples employed together with the tool required to fasten them frequently be-

come lost in transit, resulting in a large 55 number of complaints and replacements. In the numerous endeavors which have been made to form hard steel posts with integral fabric securing tongues, it has been found that the tongues will either break off during the forming operation or when bent back over a wire to retain it in engagement with the post. For these and other reasons the forming of integral tongues on hard steel posts and the manipulation of such tongues 60 after forming to have holding engagement with a fence wire have been impractical, and manufacturers have therefore continued with the use of the annoying special fence holding staples.

An object of the invention is the provision of a simple, efficient and economical method of producing integral fabric securing tongues on hard steel posts and to render such tongues bendable in a direction necessary to lock or retain a fence wire to a post without liability of breaking the tongue. A further object of the invention is the provision of a simple and efficient means for practicing said method.

The invention is fully described in the following specification, and while the method is capable of being practiced by different means, a preferred means for practicing the same is illustrated in the accompanying drawings, in which,—

Figure 1 is a fragmentary elevation of a stamping means embodying the invention, with a part in vertical section; Fig. 2 is a top plan view of the work guide and recessed tongue forming part; Figs. 3 and 4 are views of a portion of the forming mechanism and a work-piece being acted on with the punch at different positions in a tongue forming movement thereof; and Fig. 5 is a fragmentary side elevation of the working portion of the punch.

Referring to the drawings, 1 designates a hard steel fence post, which may be of T, L or other form in cross-section, as desired. 100 The post has a face or side thereof intended for positioning next to the fencing to be hung and provided with a plurality of integral longitudinally spaced wire engaging tongues 2 which are struck outwardly therefrom.

Each tongue 2 comprises an inner end or body portion *a* which extends outwardly

from the post at a slight angle or incline to its fabric engaging face, and an outer end portion *b*, which has a slight inward angle with respect to the portion *a* and is preferably disposed in a plane which more nearly approaches a parallel with the post face than does the plane of the body portion *a*. The spacing of the outer end portion *a* of the tongue from the post face, substantially at the point of angle *c* of the tongue, should be substantially equal to the diameter of the line wire of a fabric to be hung so that a wire disposed within such space will seat against the tongue at substantially the point of angle *c*. A bending of the tongue end *b* over the wire secures the wire to the post and this is usually accomplished by giving the end portion of the tongue one or more blows on its outer side with a hammer, the bending action taking place at or adjacent to the point of the angle *c* between the two tongue portions. In practice it is found preferable to dispose the body portion *a* of the tongue at substantially a 20° angle to the post face and to dispose the end portion *b* of the tongue at substantially a 3° angle to the face of the post, with the space between the tongue portion *b* and the post face narrower at its inner end than at its outer end. While we have particularly specified the preferred angles between the face of the post and the different portions of the tongue, it will be understood that the invention is not intended to be restricted to such angles.

The provision of the tongue with the initial back angle *c* is found in practice to be very important, for without it the tongue will in nearly every instance be broken off when attempt is made to bend its end back over the wire, and furthermore, it is found important that the initial back bend be formed simultaneously with the forming of the main tongue, or substantially so, and not subsequently thereto. The reason for this, so far as understood, is that in bending hard steel, one-half of the cross-sectional area of the article at the point of bend is placed under compression and the other half is placed under tension, and if a back or reverse bend is then given to the article in coincident relation to the former oppositely bent portion, a tensional stress is given to the previously compressed portion and breakage occurs. If, however, an initial back bend is given to the article at the time of forming, such back bend may be later increased without breaking off as the bend continues in the direction in which started.

With my method a tongue is struck outwardly from the piece of steel and the small reverse or back bend *b* is simultaneously formed in the tongue; consequently when a wire is engaged with a tongue and the end of the tongue bent over the wire in holding engagement therewith, such bending action

is a continuation of the operation that formed the tongue and not a reversal thereof that would cause breakage.

The apparatus preferably employed for practicing the method above described is used in connection with a power press and includes a punch 10 carried by and projecting downward from the press ram 11, and the cooperating tongue forming parts carried beneath the punch by a bed-plate 12. The bed-plate is recessed on its top to receive a work guide and die carrying plate 13, which projects above the top surface of the bed-plate and is provided in its top throughout its length with a work receiving and guiding groove 14, the bottom of which, in the present instance, is flush with the top of the bed-plate. The width of the groove 14 is preferably slightly greater than the width of the work to be operated on, to allow for differences in size, and one wall of the groove has a pressure strip 15 yieldingly projecting therefrom to bear against the adjacent side of a work-piece to yieldingly hold it properly positioned within the groove.

An elongated die block 16 is mounted in a recess provided in the plate 13 in the bottom of its guide groove 14 and extends lengthwise of the groove with its top flush with the bottom thereof. The die block 16 is formed in its top with a recess 17, which conforms to the shape of the tongue 2 to be formed in a post or work-piece 1, and the walls of the recess have shearing cooperation with the punch 10 to punch the tongue from the work bar when the punch is lowered, as is well understood in the stamping art. The forward end of the die block recess 17, or that toward which a formed tongue is moved as the work-piece 1 is fed over the bed-plate to bring successive portions thereof into tongue forming position, opens into a broadened recess 18 in the die block through which the formed tongues pass as the work piece is advanced. The recess 18 is continued through the registering portion of the plates 13 and 12. The shape of the tongue forming recess 17 is such that a tongue after being formed, can pass therefrom lengthwise of the die plate, and into and through the registering recess 18.

From experiments it has been found that the best results have been obtained by giving the nose portion of the punch for about $\frac{1}{3}$ of its length a rearward and upward incline of approximately 3° from a horizontal or from the plane of the work surface to be acted on, the heel portion or remaining length of the working surface of the punch an angle of about 20° from a horizontal or from the plane of the work surface to be acted on, as shown in Fig. 5. If the angles of the nose and heel portions of the working end of the punch are varied even slightly from those designated it is found

that breakage of the tongues from the work during the punching operation is more apt to occur, the amount of breakage increasing with the extent of variance of the working faces of the punch from the angles noted.

During a tongue punching operation the stripping of the sides of the tongue from the stock progressively continues inward from the nose portion of the tongue, and when the nose portion of the tongue has been swung downward a sufficient distance to strike the bottom of the die block recess 17 its further downward movement is stopped thereby and the angled portion of the punch between the working faces thereof then acts, during the continued downward movement thereof, to bend the tongue to form the relatively angled portions *a* and *b* thereof, the tongue assuming the shape or angle of the working face of the punch as illustrated in Figs. 1 and 4. It is apparent that the progressive stripping of the tongue from the stock causes a progressive downward bending of the tongue from the stock, as illustrated in Fig. 3, and that the bending of the tongue to form the nose portion *b* thereof imparts a reverse bend to the metal in the tongue from that which is occasioned by the tongue stripping action. It is found, however, that as the two bending actions take place in the same operation and practically simultaneously, the tongue will not be broken in two by the back bending action, as would be the case if such bending action were made in a subsequent operation.

It is found quite important in practice that the portion of the die block with which the end of the tongue coacts in the back bending operation shall be yieldable under abnormal strains and that the top surface of such portion shall be elevated slightly above the bottom of the communicating recess 18. To accomplish this a yielding pressure block 20 is mounted in registering bottom openings in the plate 13 and die block 16 in position to form the bottom of the die block recess 17 and is carried by a head block 21 mounted in an opening in the bed-plate 12 and receiving the upper end thrust of a coiled compression spring 22 that is mounted in a housing 23 secured to and depending from the under side of the bed-plate. The lower end thrust of the spring 22 is against an adjusting block 24, the adjustment of which to vary the tension of the spring is accomplished by the turning of a screw 25, which is threaded through the bottom of the housing. The tension of the spring 22 is sufficient to resist a lowering of the pressure block 20 during normal forming conditions but permits a lowering of the block during abnormal conditions or to compensate for a varying in thickness of the stock metal from which the tongue is formed, it being understood that the punch

10 receives its full stroke for each punching operation. Should a tongue be broken off during a forming operation so that it lies on the pressure block 20 the block will lower during the next forming operation to prevent breakage of the stamping mechanism due to the presence of the broken tongue in the bottom of the forming recess. Should the stock from which the tongue is formed be thicker than usual the pressure block 20 will lower to compensate for the same and the difference in the normal elevation of the top surface of the block in the bottom of the tongue withdrawing recess 18 will permit an oversize tongue to pass through such recess without tending to raise the stock 1 above the bottom of the guide groove 14 in which it rests.

If the stock operated on is of T-bar form it is preferable to form the successive tongues first on one and then on the other of the face flanges of the bar. If the tongues are formed on the T-bar in this manner the tongue forming press may be provided with a plurality of tongue forming parts arranged in staggered relation to simultaneously form tongues in the bar at both sides of its leg flange, or the bar may be passed through the press twice so that in one feeding operation the tongues are formed in one face flange and in the next feeding operation the tongues are formed in the other face flange. If the stock is of angle iron or channel bar form the tongues may be formed in a single line or in staggered relation as desired.

It will be understood that while we have shown and described a particular means for forming the tongues in accordance with my invention, we do not wish to be restricted to such means as the method may be practiced by numerous other means so long as the stripping of the tongue from the stock and the back bending of its nose portion takes place in the same operation and simultaneously or substantially so.

Having thus described our invention, what we claim as new, and desire to secure by Letters Patent, is,—

1. The method of making a metallic fence post or similar article with an integral tongue for subsequent back bending, which consists in taking a hard steel blank, stripping a tongue throughout its length from the blank by a punching operation, and in the same operation imparting an initial back bend to the outer end portion of the tongue toward the opening from which it is stripped and in the direction of intended subsequent bending.

2. The method of making a metallic fence post or similar article with an integral tongue for subsequent back bending, which consists in taking a blank of hard high-carbon steel, punching a tongue outwardly

from the blank, and causing the forming punch during the punching operation to co-operate with an opposed resisting means to impart an initial back bend to the outer end 5 portion of the tongue toward the opening from which it is punched.

3. The method of making a metallic fence post or similar article with an integral tongue for subsequent back bending, which 10 consists in taking a hard steel blank, progressively stripping a tongue from the blank rearwardly from the nose portion of the tongue, and at the same time bending the tongue outward at a slight angle to the 15 blank, and simultaneously imparting a back bend to the end portion of the tongue toward the opening from which it is stripped.

4. The method of forming hard steel fence post stock with an integral tongue for subsequent back bending, consisting in punching the tongue from the stock to assume an angle of approximately 20° thereto, and at the same time imparting an initial back bending to an outer end portion of the 25 tongue to assume an outward angle of approximately 3° to the stock.

5. The method of forming hard steel fence post stock with an integral tongue for subsequent back bending, consisting in punching the tongue from the stock to assume an angle of approximately 20° thereto, and at the same time imparting an initial back bend to an outer end portion of the tongue 30 constituting substantially $\frac{1}{3}$ of its length to assume an outward angle of approximately 3° to the stock.

6. An apparatus for forming tongues on hard steel stock, including a recessed die, and a punch for cooperating with the die 40 to form a tongue on the stock, said punch having a nose portion receding rearwardly at substantially a 3° angle to the face of the stock operated on and having a heel portion extending rearwardly from the nose portion

at substantially a 20° angle to the stock 45 face.

7. An apparatus for forming tongues on hard steel stock, including a recessed die, and a punch for cooperating with the die to form a tongue on the stock, said punch having substantially a third of the length of its working end forming a nose portion and the remainder of its length forming a heel portion with the nose portion receding rearwardly at a slight angle to the face of the 55 stock operated on and with the heel portion extending rearwardly from the nose portion at a greater angle to the stock face.

8. An apparatus for forming tongues on hard steel stock, including a recessed die, 60 and a punch for cooperating with the die to form a tongue on the stock, said punch having substantially a third of the length of its working end forming a nose portion and the remainder of its length forming a 65 heel portion with the nose portion receding rearwardly at substantially a 3° angle to the face of the stock operated on and with the heel portion at substantially a 20° angle to the stock face.

9. An apparatus for forming tongues on hard steel stock, including a recessed die having the bottom of its recess adapted to yield under predetermined pressure, and a punch for entering the die recess and cooperating with the die to progressively strip a tongue from a stock piece rearwardly from the tongue end and cooperating with the yieldable recess bottom to impart a predetermined back bend to the free end portion 80 of the tongue during the stripping operation and toward the opening from which it is stripped.

In testimony whereof we have hereunto signed our names to this specification.

VERNON HOXIE.
MARTIN C. EPKE.
